Attorney.

UNITED STATES PATENT OFFICE.

LOUIS H. BLOOD, OF CINCINNATI, OHIO, ASSIGNOR TO THE CESTERLEIN MACHINE COMPANY, OF CINCINNATI, OHIO.

MECHANICAL MOVEMENT.

1,403,480.

Specification of Letters Patent. Patented Jan. 17, 1922.

Application filed December 6, 1919. Serial No. 343,022.

To all whom it may concern:

Be it known that I, Louis H. Blood, a citizen of the United States, residing at Cincinnati, Hamilton County, Ohio, have 5 invented certain new and useful Improvements in Mechanical Movements, of which the following is a specification.

This invention, devised with special reference to the production of feeding motion 10 in milling-machines will be readily understood from the following description taken in connection with the accompanying drawing in which:

Fig. 1, is a diagram illustrating the principle of my invention; and

Fig. 2, is a side elevation of the moving mechanism shown in its application to the ram of a milling-machine, constituting the best mode in which I have contemplated 20 applying the principle of my invention.

In the drawing confining attention exclusively to Fig. 1:

1, indicates a machine-part to be reciprocated in a right line in one direction a given 25 distance at continuous speed and in the other direction at increased speed, this part being hereinafter referred to as the carriage;

2, a roller provided on the carriage;

3, a driving-shaft, journaled in a fixed 30 bearing and to be revolved continuously by power;

4, a cam fast upon the driving shaft and having its periphery engaging the periphery of roller 2, the contour of the cam being 35 a volute comprehending the major portion of the periphery of the cam;

5, a second cam on the driving shaft, this second cam not, however, engaging roller 2, a portion of the periphery of this second 40 cam being in the form of a volute;

6, a first fixed pivot;

7, a second fixed pivot, the axes of the two pivots being parallel with each other and parallel with the axis of the driving 45 shaft, the axes of these two pivots being in a line parallel with the line of reciprocation of the carriage;

8, an arm pivoted on pivot 6;

9, an arm pivoted on pivot 7;

50 10, a link pivotally connecting the two arms 8 and 9;

11, an extension of link 10;

12, a housing adjustably fixed on extension 11;

13, a roller mounted in this housing and engaging the periphery of cam 5;

14, a spring in link 10 to permit of the yielding extension of the length of the link endwise with reference to the pivot uniting the link with arm 9;

60

15, a screw in link 10 for adjusting the compression of the spring;

16, the journal of roller 2, this journal projecting sidewise of the carriage; and

17, an arm constituting in effect a prolongation of arm 9, this arm 17 bearing against journal 16.

The two rollers 2 and 13 are on opposite sides of shaft 3. Journal 16 forms an abutment disposed between arm 17 and shaft 3 70 and engaged by arm 17 on that side away from the shaft 3.

When the shaft and cam 4 are rotated in the direction of the arrow, the carriage is moved to the right a distance represented 75 by the throw of the cam 4. When the cam shall be so turned as to give to the carriage its maximum stroke then the minor radius of cam 5 will engage roller 13 and cause the carriage to make its returned motion at 80 quickened speed. The two cams are complementary to each other and are assumed as being selected or designed to give to the carriage its desired degree of slow advancing motion through proper distance, 85 and its return motion at higher rate of speed.

It is desired that the carriage, in being given its motions, be engaged simultaneously by cam 4 and by arm 17. To provide 90 against inaccuracies of construction of the cams, and to provide against their wear, the link 10 is rendered elastic endwise by the spring 14, and the spring may be adjusted in compression by the screw 15, the 95 result being that the engagement between journal 16 and arm 17, and the engagement between roller 13 and cam 5 are always maintained and lost motion of parts is prevented.

105

This movement has been devised with special reference to the movement of the ram of a milling-machine, which ram carries the cutter-spindle, the movement giving the endwise feeding movement and the quick return movement to the ram, the ram reciprocating in a path at right angles to the axis of the cutter-spindle. This em-

bodiment of my invention may be understood from an inspection of Fig. 2 in which the same numerals of reference are employed as in Fig. 1 along with additional numerals of reference.

Continuing with the drawing:

- 18, indicates a column forming the body or frame of the milling machine;
19, a ram-guide formed in the column;
10 20, a ram fitted to reciprocate in the ram-guide;
15 21, a sleeve mounted for vertical adjustment in the ram-guide in a line at right angles to the path of reciprocation of the ram;
22, the cutter-spindle journaled in the sleeve; and 23, an adjusting device connecting the ram with the carriage 1.

In the exemplifying device illustrated in Fig. 2 the driving shaft 3 is journaled in the column below and at right angles to the ram, and the carriage 1 is adjustably fixed to the ram. The two pivots 6 and 7 are disposed below the driving shaft, in a plane 25 parallel with the path of reciprocation of the ram.

The pair of cams are to be so selected and conformed as to give to the ram certain regular or irregular oscillating motions, depending upon the predetermined peculiar requirements of the work which the machine is to perform. The relation of the cutter-spindle to the carriage is adjustable to suit the stroke required.

Having thus described my invention, what I claim as new and desire to secure by Letters Patent of the United States, is:—

1. A mechanical movement comprising a driving shaft, a carriage, a first cam fast 40 on the driving shaft for giving forward motion to said carriage, a second complementary cam fast on the driving shaft for giving return motion to the carriage, an abutment on the carriage engaged by the first cam, a pair of fixed pivots, a pair of arms mounted on these pivots, a link pivoted to these two arms, a second abutment on the carriage, an arm in extension of one of said arms which engages the second abutment, 45 and an abutment on the link which engages the second cam, combined substantially as set forth.

2. A mechanical movement comprising a driving shaft, a carriage, a first peripheral 55 volute cam fast on the driving shaft for giving forward motion to the carriage, a second complementary peripheral cam fast on the driving shaft for giving return motion to the carriage, an abutment on the carriage engaged by the first cam, a pair of fixed pivots, a pair of arms mounted on these pivots, a link pivoted to these two arms, a second abutment on the carriage, 60 an arm in extension of one of said arms which engages the second abutment, and

an abutment on the link engaged by the second cam, combined substantially as set forth.

3. A mechanical movement comprising a driving shaft, a carriage, a first cam fast 70 on the driving shaft for giving forward motion to the carriage, a second complementary cam fast on the driving shaft for giving return motion to the carriage, an abutment on the carriage engaging the first 75 cam, a pair of fixed pivots, a pair of arms mounted on these pivots, a link pivoted to these two arms, a second abutment on the carriage, an arm in extension of one of said arms which engages the second abutment, 80 a housing carried by the link, and adjustable with reference thereto, and a roller carried by the housing and engaging the second cam, combined substantially as set forth.

4. A mechanical movement comprising a driving shaft, a carriage, a first cam fast on the driving shaft for giving forward motion to the carriage, a second complementary cam fast on the driving shaft for giving return motion to the carriage, an abutment on the carriage which is engaged by the first cam, a pair of fixed pivots, a pair of arms mounted on the pivots, a link pivoted to these two arms, a spring in said link 95 for permitting it to elastically change its length, a second abutment carried by the carriage, an arm in extension of one of said arms which engages the second abutment and an abutment carried by the link and 100 engaging the second cam, combined substantially as set forth.

5. A mechanical movement comprising a driving shaft, a carriage, a first peripheral volute cam fast on the driving shaft for 105 giving forward motion to the carriage, a second complementary peripheral cam fast on the driving shaft for giving return motion to the carriage, a roller carried by the carriage and engaging the first cam, a pair 110 of fixed pivots, a pair of arms mounted on these pivots, a link pivoted to these two arms, a prolongation of the roller journal carried by the carriage, an arm in extension of one of said arms and engaging the 115 said prolongation of the roller journal, and a roller carried by the link and engaging the second cam, combined substantially as set forth.

6. A mechanical movement comprising a 120 driving shaft, a carriage, a first peripheral cam on the driving shaft which by its conformation determines the nature of the outward movement of the carriage, an abutment on the carriage engaged by said cam, 125 and means for effecting and determining the nature of the return movement of the carriage, said means comprising an oscillating structure which is engaged and moved by the carriage on the outward movement 130

thereof, an abutment on the oscillating structure, and a second cam complementary to the first, said second cam being fixed on said shaft and adapted to engage the last mentioned abutment to effect the return stroke of the carriage.

7. A mechanical movement comprising a carriage, a driving shaft, an abutment on the carriage, a cam on the driving shaft 10 adapted to engage said carriage to effect outward movement of the carriage, an oscillating structure, a second abutment on the carriage which engages the oscillating structure and causes said structure to move with 15 the carriage on the outward movement of the latter, a second cam complementary to the first mounted on the driving shaft and an abutment on the oscillating structure adapted to be engaged by said second cam, said 20 second cam adapted to engage the last mentioned abutment to return the oscillating structure and carriage to their respective initial positions.

8. In a mechanical movement, a driving 25 shaft, a carriage, an abutment on the carriage, a peripheral cam which engages said abutment and effects and determines the nature of the outward movement of the carriage, a second peripheral cam complementary 30 to the first also fixed on the driving

shaft, and means engaged and moved by the carriage on the outward movement of the latter, said last mentioned means adapted to be engaged by the second cam and returned to initial position along with the carriage. 35

9. In a mechanical movement, a carriage, a driving shaft, a pair of peripheral cams on the driving shaft one of said cams adapted to engage an abutment on the carriage to effect the outward movement of the latter, 40 and means which is moved by the carriage on the outward movement thereof, but which is engaged by the second cam and is actuated by said second cam to restore the carriage to initial position. 45

10. In a mechanical movement, a driving shaft, a carriage and a pair of complementary peripheral cams, one of said cams acting directly upon an abutment carried by the carriage to effect the outward movement 50 of the carriage and an oscillating structure which is engaged and moved by the carriage on the outward movement of the latter and which is engaged by the second cam when the carriage is to be returned to initial position. 55
